UNITED STATES PATENT OFFICE.

ARTHUR L. HALLIDAY, OF YONKERS, AND JOHN B. NEIL, OF NEW YORK,
N. Y., ASSIGNEES TO THE BIGELOW CARPET COMPANY, OF CLINTON,
MASSACHUSETTS.

DESIGN FOR A CARPET.

SPECIFICATION forming part of Design No. 12,426, dated August 23, 1881.
Application filed July 14, 1881. Term of patent 3½ years.

To all whom it may concern:

Be it known that we, ARTHUR L. HALLIDAY, of Yonkers, in the county of Westchester and State of New York, and JOHN B. NEIL, of the city, county, and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having our new design.

The stripe B is composed of the band O, containing a series of parallel bars running across it; also, of the band m, ornamented with a pattern resembling a close-set picket-fence, each picket containing a circular figure near its end, and with a row of ornamental figures set between the points of the pickets. The stripe B also contains the band n, ornamented with diagonal cross-lines; also, the band e, containing a series of figures projecting from the edges toward the center, and resembling the stalactites and stalagmites in a cave; also, the band l, containing a series of rectangles set edgewise.

The stripe A contains the bunch of flowers D, touching the lattice-work f, and having the mossy branch g projecting. The figure e in this stripe is a central leaf surrounded by mossy sprays. The figure C has a center, b, of circular flowers resting on a rectangular lattice-work, a, and having projecting from it the leafy branch j, the twig i, and the leaf d.

The figures just described are repeated at intervals throughout the stripe A.

The stripe h contains an ornamentation of lines crossing each other diagonally.

We claim—

1. The design for carpets, consisting of the figure O, substantially as shown. 40
2. The design for carpets, consisting of the figure m, substantially as shown.
3. The design for carpets, consisting of the figure e, substantially as shown. 45
4. The design for carpets, consisting of the figure l, substantially as shown.
5. The design for carpets, consisting of the stripe B, containing figures O m n e l, substantially as shown. 50
6. The design for carpets, consisting of the figure c, substantially as shown.
7. The design for carpets, consisting of the figures C and D, substantially as shown. 55
8. The design for carpets, consisting of the figure C, containing figures a b d j i, substantially as shown.
9. The design for carpets, consisting of the stripe A, containing figures C a b j d i D f g e, substantially as shown. 60
10. The design for carpets, consisting of the stripe h, substantially as shown.
11. The design for carpets, consisting of the stripe h, stripe A, containing figures C a b j d i D g e, and stripe B, containing figures l, e, n, m, and O, substantially as shown. 65

ARTHUR L. HALLIDAY.
JOHN B. NEIL.
